United States Patent Office

Des. 225,388
Patented Dec. 5, 1972

225,388

TAPE CASSETTE STORAGE ALBUM

Gerald L. Price, 16610 Calneva Drive,
Encino, Calif. 91316

Filed Apr. 17, 1970, Ser. No. 22,480

Term of patent 14 years

Int. Cl. D3—99

U.S. Cl. D87—1

FIG. 1

FIG. 3

FIG. 1 is a perspective view of a tape cassette storage album showing my new design in a partially opened condition;

FIG. 2 is a rear perspective view thereof in a partially closed condition, the side opposite being substantially similar to the side shown;

FIG. 3 is a front elevational view thereof in a closed condition;

FIG. 4 is a bottom view thereof in a fully opened condition; and

FIG. 5 is a top view thereof in a closed condition.

I claim:

The ornamental design for a tape cassette storage album, as shown and described.
